UNITED STATES PATENT OFFICE.

ARTHUR E. WILDE, OF NEW YORK, N. Y.

SAFETY-RAZOR-BLADE HOLDER.

1,113,851.

Specification of Letters Patent. Patented Oct. 13, 1914.

Application filed March 21, 1913. Serial No. 756,051.

To all whom it may concern:

Be it known that I, ARTHUR E. WILDE, a citizen of the United States, residing at New York city, in the county of New York and 5 State of New York, have invented new and useful Improvements in Safety-Razor-Blade Holders, of which the following is a specification.

This invention relates to devices for holding and manipulating safety razor blades while the same are being stropped, and has for its object to provide a simple, cheap and efficient device of this character, whereby, the various makes of safety razor blades now 10 in use may be rigidly and conveniently held during the operation of stropping.

To these ends the invention consists in the novel details of construction and combination of parts more fully hereinafter described and particularly pointed out in the 15 claim.

Referring to the accompanying drawings forming a part of this specification in which like numerals designate like parts in 20 all the views:—Figure 1 is a perspective view of my improved device shown holding a safety razor blade. Fig. 2 is a longitudinal sectional view of the blade holding end of the device, and Fig. 3 is a cross sectional 25 view thereof.

My improved device consists of the clamping portion 1 and the handle portion 2, formed of a suitable material such as wood. The clamping portion is preferably of triangular shape in cross section, and is split or 30 bifurcated longitudinally as at 3, to a point at the end of the handle to provide two oppositely disposed clamping jaws 4 between which the device is adapted to grasp a flat 35 safety razor blade 5.

Resilient means are provided for forcing the jaws toward each other to cause them to grasp the razor blade therebetween. As here shown each of the jaws is provided on 40 its outer end with reduced coöperating neck portions 6 and at their inner ends with a reduced neck portion 7, around which portion are wrapped elastic bands 8. These 45 bands exert sufficient pressure upon the reduced portions to frictionally hold the blade 50 between the jaws with such firmness as will

prevent its accidental displacement during the operation of stropping. The provision of the said bands also admits of the introduction of the blade between the jaws without the necessity of removing the bands, and to facilitate this introduction of the blade a curved notch 9 is provided in the jaws as shown in Figs. 1 and 2, whereby a depression is formed to receive a corner of the blade 55 when the edge thereof is arranged so as to extend in the direction of the length of the slit between the jaws.

I prefer to construct the device as shown on the drawings; that is with a relatively 60 long handle and to provide the clamping jaws with the beveled side portions whereby, opposite sides of the razor may be conveniently presented to the strop at the desired angle during the operation of stropping.

When it is desired to strop a safety razor blade the clamping jaws are first sprung apart against the action of the rubber bands for a sufficient distance, to admit of the 65 introduction of the razor blade therebetween.

It is obvious that those skilled in the art may vary the details of construction and arrangement of parts without departing from the spirit of my invention and therefore I 70 do not wish to be limited to such features except as may be required by the claim.

What is claimed as new is:

A safety razor blade holder comprising a 75 relatively thin handle portion and a relatively wide pair of flexible jaws formed integral with one end of the handle, said jaws being each substantially semi-pyriform in cross section and provided at their free ends with reduced coöperating neck portions and 80 further provided in one edge with a notch 90 to take the corner portion of a razor blade, and elastic bands embracing the said neck portions and the jaws at their point of connection with the handle.

In testimony whereof I affix my signature in presence of two witnesses.

ARTHUR E. WILDE.
